(57) **CLAIM**

The ornamental design for a portable electric drill, as shown and described.

DESCRIPTION

FIG. 1 is a perspective view of a portable electric drill showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The Makita trademark, which forms a part of the claimed design, is a registered trademark of the Makita Corporation.
